(57) CLAIM

The ornamental design for a multiple chamber infusion pump, as shown and described.

DESCRIPTION

FIG. 1 is a front view of a multiple chamber infusion pump showing our new design;

FIG. 2 is a side view thereof;

FIG. 3 is a top plan view thereof;

FIG. 4 is a front view thereof, with the cover and cap removed. A section of the front is removed to show the inside surface detail of the infusion chambers;

FIG. 5 is a side view thereof, with a section of the side removed to show the inside surface details of the infusion chamber.

FIG. 6 is a top view thereof; and,

FIG. 7 is bottom plan view thereof.
